(57) **CLAIM**

The ornamental design for a rod buckle, as shown and described.

DESCRIPTION

FIG. 1 is a top, front and right side perspective view of a rod buckle showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The unevenly dashed broken lines define the boundaries of enlarged views and form no part of the claimed design.

1 Claim, 9 Drawing Sheets
